TRACTOR SHOES

Ward W. Weller, Wellesley, Mass.

Application July 17, 1958, Serial No. 749,145

5 Claims. (Cl. 305—53)

This invention relates to so-called tractor shoes of the kind to be mounted on the endless track of a track-laying vehicle.

The conventional mode of achieving effective traction in a track-laying vehicle is by way of individual shoes that are arranged in an articulated assembly about the track, and the shoes are removably related to the track to enable individual repair and replacement to be accomplished. It is common practice to form each such shoe with a so-called sole plate and a grouser which is merely a bar-type projection on the ground-engaging side of the sole plate, and this grouser is what digs into the ground during the course of movement of the track of the vehicle.

In the course of engaging the ground, the plate of the shoe is subjected to a great deal of stress so far as upward bending at the side is concerned, particularly on uneven ground. Conventionally, the shoe is joined to the track by bolts occupying openings in the sole plate, and there is a great deal of stressing of the walls in the plates of the shoes where the bolts are located, especially in those instances where the portion of the shoe having the bolt openings is composed of manganese steel.

The primary objects of the present invention are to increase the traction efficiencies of shoes of the foregoing kind, to build into the shoe a great deal of resistance to bending, and to prevent to a large degree distortion of the aforementioned bolt openings. Specifically, it is the object of the present invention to construct a shoe of the foregoing kind with a grouser having a sloped leading or forward face, having end sections on the sole plate that are disposed in inclined planes, having bolt openings that are work hardened and having all corners rounded. Resultantly, there is easy entry of the grouser into and out of the ground with practically no hang-up due to right-angled corners, the sole plate is inherently resistive to vertical bending, and the bolt holes are inherently resistive to stretching or distorting.

Other and further objects of the present invention will be apparent from the following description and claims and are illustrated in the accompanying drawings which, by way of illustration, show preferred embodiments of the present invention and the principles thereof and what is now considered to be the best mode contemplated for applying these principles. Other embodiments of the invention embodying the same or equivalent principles may be used and structural changes may be made as desired by those skilled in the art without departing from the present invention and the purview of the appended claims.

In the drawings:

Fig. 1 is a top plan view of a track shoe constructed in accordance with the present invention;

Fig. 2 is an end view taken on the line 2—2 of Fig. 1;

Fig. 3 is a front elevation taken on the line 3—3 of Fig. 1;

Figs. 4 and 5 are sections taken respectively on the lines 4—4 and 5—5 of Fig. 1;

2

Fig. 6 is a schematic view illustrating the action of the present shoe;

Fig. 7 is a sectional view taken on the line 7—7 of Fig. 6; and

Fig. 8 is a series of sectional views showing work hardening of bolt holes.

The present invention is illustrated in Figs. 1 to 3 inclusive as embodied in a shoe 10 of the kind to be removably connected to the endless track T, Fig. 6, of an overland track-laying vehicle such as a bulldozer, tractor or the like, and reference will be hereinafter made to Figs. 6 and 7 explaining some of the advantageous results of the present invention.

The shoe 10 represents a one-piece casting of manganese steel or the like and includes a so-called sole or tread plate 12 which is the portion of the shoe which will lie normally in a horizontal plane when the shoe is mounted on the track T. Except for certain projections to be described, the sole plate is of substantially uniform cross-section thickness. While the shoe of the present invention is conveniently a cast part, the same can be forged if desired, or fabricated by various techniques.

As will be observed in Fig. 1, the plate 12 is generally rectangular in plan view, and the left and right side and rear (trailing edge) limits thereof are defined by a continuous raised bead or bulb edge rib 15 of rounded cross-section throughout which greatly strengthens and reinforces the plate 12. This rib is located on what constitutes the ground engaging face of the shoe, and the provision of such a raised edge on the plate 12 effectively stiffens the latter and establishes a great deal of resistance to bending or twisting of the plate 12 during the course of field operation. By rounding the rib 15, as well as all corners of the shoe as will be noted, the shoe is prevented from "hanging up" on uneven ground, rock beds, and so on.

Projecting vertically from what constitutes the ground engaging face of plate 12 is a grouser 20. Fig. 2, and this grouser represents the essential tread or ground digging part of the shoe which will enter the ground during the course of movement of the vehicle, thereby introducing forward movement of the vehicle as will be recognized from Fig. 6. The grouser has a flat upper edge 20F, Fig. 1 which will first dig into the ground, and the grouser extends from one side of the shoe to the other. The two opposite grouser ends 20A and 20B, Fig. 3, are inclined inwardly proceeding in a direction away from the sole plate 12, which contributes to easy entry of the grouser into and disengagement from the ground, and the upper or free corners of the grouser are rounded at 20R for the purpose mentioned above.

As will be observed in Fig. 2, the upper edge of the grouser is relatively narrow, but the grouser is substantially widened and thickened in the lower sections adjacent the sole plate 12. The end or side surfaces of the grouser are triangulated rearwardly toward the rib 15 to afford end webs or gussets disposable in a vertical plane, and these webs have rear edges which curve downwardly and rearwardly at 20R1, Fig. 2, to merge into the side extensions of the rib 15. By so widening the ends of the grouser to provide flat gussets WG, the latter represent flat ground-penetrating plates serving to establish resistance to side slippage in contrast to a grouser having merely narrow ends.

Inwardly of the gussets WG, the rear side of the grouser, Fig. 2, is vertically straight at 20S so as to be substantially perpendicular to the plane of the plate 12, but it will be noted in Fig. 2 the front side or leading side 20L of the grouser is angled rearwardly proceeding from the sole plate toward the upper edge of the grouser. Hence, as will be observed in Fig. 6, a grouser 20 at the front of the vehicle track T just enters

ing the ground will do so in an even unabrupt fashion in contrast to a rather violent and abrupt thrust in those instances where the leading or front face of the grouser is perpendicularly straight as the rear or leading face is perpendicularly straight. I have found that the angle of inclination for the front face of the grouser should be between 45° and 60° and preferably 60° for the best effect. It will be appreciated that the gussets or webs described above have their narrow ends terminating at the narrow edge of the grouser and hence will easily enter and withdraw from the ground.

An important feature of the present invention resides in cantilevering the ends of the sole plate 12. Thus, referring to Fig. 3, it will be observed that the medial portion of the sole plate 12 is adapted to be disposed in a substantially flat and truly horizontal plane, whereas under such circumstances the respective left and right hand end sections 12L and 12R thereof are tipped or bowed upwardly in divergent inclined planes in respective directions proceeding outwardly from the medial section of the sole plate, and this effect is particularly evident in Fig. 4. Stated in other words, the ground engaging faces of the sections 12L and 12R will lie in planes that are inclined downwardly proceeding outwardly from the horizontal medial section of the sole plate when the shoe 10 is turned with the grouser downward, and hence as shown in the somewhat diagrammatic section of Fig. 7, the left and right hand end sections of the sole plate will be those that first engage the ground. Accordingly, any tendency due to unevenness of the ground or unevenness of the vehicle to bend or distort the sole plate will be resisted by the bowed ends of the sole plate.

Various different methods of articulating a plurality of shoes on a track have been resorted to in the past, and these various modes of articulation can be resorted to under the present invention. However, it should be pointed out that advantageously in accordance with the present invention the leading end of the shoe 10, Fig. 2, is provided with a downwardly bowed front flange 30 formed with a pair of spaced mounting sockets 31 which open at the free or leading edge of the front flange 30. The sole plate 12 at the remote rear portion thereof is bowed concave upwardly at 35, Fig. 2, in order to engage complementally the upper surface of the front flange 30 of the trailing shoe 10 in the articulated assembly.

The shoe assembly is commonly bolted to the track of the vehicle, and it has been found that the bolt openings formed in the sole plates of the shoes have tended to become stretched and distorted after prolonged use due to the rather severe bending and twisting actions that occur. This distortion and expansion of the bolt openings occurs particularly in the case of manganese steel, which is a relatively ductile material, and in any event it is not long before the shoes must be somehow retightened. In accordance with the present invention, I overcome this particular problem by initially forming the various bolt openings as 36 in the sole plate 12, Fig. 1, of an undersized diameter compared to the fastening bolts that will be passed through the openings 36 in connecting shoes as 10 to the track. Subsequent to this, and before final assembly, a pin P, Fig. 8, having the diameter of the fastening bolts is then driven through the undersized openings 36 to enlarge and work-harden the same at the areas WH immediately surrounding the bolt openings. Consequently, the final openings 36 in a sole plate 12 of manganese steel or like ductile ferrous metal alloy will be hardened sufficiently to resist the deforming action of the fastening bolts in use.

Many advantages of the present invention have been stressed in connection with the various structural details. It should be further mentioned that the downward line or force of the grouser into the ground by inclining the front face of the grouser affords at least thirty percent

more depth of compaction which in turn affords that much more traction. Further, there is a greater increase in flotation since the tractor or other vehicle is being forced upward and forward with less expenditure of power, and wear is distributed more evenly over the entire forward surface of the grouser resulting in much longer life before re-grousering is required.

The use of the raised rib 15 about the periphery of the ground engaging face of the plate 12, the cantilevered end sections of the sole plate and the rounded corners, instead of internal ribbing for additional strength, reduces the tendency of the shoe to be clogged with dirt and other soft material which eventually reduces traction; and the cantilevered ends achieve a great deal of resistance to bending without the added weight of special ribs. In other words, great strength is achieved by the peripheral rib 15 which cooperates with the grouser to define a dish-shaped cavity in the shoe unoccupied by any other projections. Additionally, the work-hardened bolt holes reduce to a minimum repair and replacement due to the common stretching.

Hence, while I have illustrated and described a preferred embodiment of my invention it is to be understood that this is capable of variation and modification, and I therefore do not wish to be limited to the precise details set forth, but desire to avail myself of such changes and alterations as fall within the purview of the following claims.

I claim:

1. A ground engaging shoe of the kind described for the track of a track-laying overland vehicle and comprising a sole plate of generally rectangular dimension, said sole plate having a medial section disposable in a horizontal plane and left and right hand side sections, said sole plate having a ground engaging face extended to all of said sections, a grouser projecting from the ground engaging face of said sole plate, a raised rib formed about the periphery of the ground engaging face of said sole plate rearwardly of said grouser, and the ground engaging faces of the left and right hand sections of said sole plate lying in respective divergent planes that are inclined upwardly proceeding outwardly of said medial section when disposed in a horizontal plane as aforesaid, the rib, the grouser, the medial, and inclined left and right sections of the sole plate presenting an inverted dish-shaped configuration to a supporting medium.

2. A shoe according to claim 1 wherein the grouser has a forward face that is inclined rearwardly proceeding upwardly from the sole plate, and wherein the sole plate is of substantially uniform cross-section thickness.

3. A shoe according to claim 2 wherein the upper end corners of the grouser are rounded, and wherein the rib is rounded to define with the grouser a dished recess unoccupied by other ribs.

4. A ground engaging shoe of the kind described for the track of a track-laying overland vehicle and comprising, a sole plate composed of manganese steel and being generally of rectangular dimension and of uniform cross-sectional thickness, said sole plate being formed with bolt receiving openings which have work-hardened side walls, said sole plate having a medial section disposable in a horizontal plane and left and right hand side sections extending outwardly of said medial section at opposite sides thereof, said sole plate having a ground engaging face extended to all of said sections, a grouser projecting upwardly from the ground engaging face of said sole plate when the medial section is in its horizontal plane, said grouser having a substantially vertically straight rear face in a plane normal to said horizontal plane and having a front face which is inclined rearwardly proceeding upwardly from the sole plate approximately at an angle of between 45° and 60° when the medial section is in its horizontal plane.

5. A ground engaging shoe of the kind described for the track of a track-laying overland vehicle and comprising, a sole plate composed of manganese steel or like ductile ferrous metal alloy and being generally of rectangular dimension and of uniform cross-sectional thickness, said sole plate being formed with bolt receiving openings which have work-hardened side walls, said sole plate having a medial section disposable in a horizontal plane and left and right hand side sections extending outwardly of said medial section at opposite sides thereof, said sole plate having a ground engaging face extended to all of said sections, a grouser projecting upwardly from the ground engaging face of said sole plate when the medial section is in its horizontal plane, said grouser having a substantially vertically straight rear face in a plane normal to said horizontal plane and having a front face which is inclined rearwardly proceeding upwardly from the sole plate approximately at an angle of between 45° and 60° when the medial section is in its horizontal plane, the upper end corners of said grouser being rounded, a raised rib of rounded cross section extending about the peripheral edge of the ground engag-

ing face of the sole plate rearward of the grouser, and the ground engaging faces of said left and right hand sections of the sole plate lying in respective divergent planes that are inclined upwardly in a direction proceeding outwardly of the opposite sides of said medial section of the sole plate, the portion of the sole plate rearwardly of the grouser presenting an inverted dish-shaped configuration to a supporting medium.

5. A track shoe comprising, a sole plate of generally rectangular configuration and having a bearing surface, 10 a grouser projecting from the bearing surface of the sole plate and extending across the sole plate so as to divide the bearing surface of the sole plate into first and second portions, the first portion of the bearing surface of the sole plate having a generally flat horizontal central section and flat inclined side sections, the inclination of the side sections being such that the outermost edges of the side sections are projected from the plane of the central section in the same direction as the projection of the

grouser, a rounded rib projecting from the periphery of the first portion of the bearing surface of the sole plate and joined to the grouser in smoothly formed gussets, the grouser, rounded rib, gussets and central and side sections of the first portion of the bearing surface of the track shoe presenting an inverted dish-shaped configuration to a supporting medium.
